UNITED STATES PATENT OFFICE.

EDWARD A. MELLINGER, OF CHICAGO, ILLINOIS.

AUTOMATIC TELEPHONE SYSTEM.

1,306,829.

Specification of Letters Patent. Patented June 17, 1919.

Application filed February 17, 1913. Serial No. 748,811.

To all whom it may concern:

Be it known that I, EDWARD A. MELLINGER, a citizen of the United States of America, and resident of Chicago, in the county of 5 Cook and State of Illinois, have invented certain new and useful Improvements in Automatic Telephone Systems, of which the following is a specification.

This invention relates to improvements in 10 telephone systems and apparatus therefor, and more particularly to automatic or semi-automatic telephone systems or combined manual and automatic or semi-automatic systems of the type in which the operation 15 of an automatic switch or automatic switches is controlled by a plurality of selective actions at the calling substation.

According to one feature of the invention a calling device is provided which is so arranged and constructed that when any one 20 of a certain number of parties is to be called a single selective action on the part of the calling party suffices to enable him to call the required party instead of his having to 25 effect a number of selective actions, as has heretofore been necessary, the plurality of selective actions on the part of the calling subscriber being dispensed with by a "setting-up" operation.

According to another feature of this 30 invention means are provided whereby after a call is effected by any type of calling device, and before the calling party has removed his receiver from the hook, an indication is given 35 him when the called party removes his receiver from the hook. Furthermore, means are provided for releasing all of the switches that have been operated if the called party is busy, and for giving a signal to the calling party to indicate that the called party 40 is busy.

The form of apparatus for carrying the 45 various features of this invention into effect, as about to be described, are adapted particularly for use in the two-wire type of automatic telephone system, such, for example, as is fully described in the specification of British Letters Patent to S. G. S. Dicker No. 1298 of 1910, though the apparatus 50 can easily be adapted, as hereinafter referred to, for use in other types of automatic or semi-automatic telephone systems.

The invention will be more readily understood from the following description, 55 taken in connection with the accompanying drawings which illustrate, by way of exam-

ple, methods of carrying this invention into effect, and in which—

Figure 1 is a front elevation of one form of calling device according to this invention. 60

Fig. 2 is a side elevation of the same.

Figs. 3 and 4 are details on an enlarged scale.

Fig. 5 is a plan of another form of calling 65 device according to this invention.

Fig. 6 is a section on the line 6—6 in Fig. 5.

Fig. 7 is a side elevation of the same, the 70 casing and some other parts being in section.

Fig. 8 is a part section on the line 8—8 of Fig. 6.

Fig. 9 is a section on an enlarged scale 75 of part of the gearing employed.

Fig. 10 is a side elevation of parts which are added to the calling device shown in Figs. 5 to 9 for carrying out certain other features of this invention.

Fig. 11 is a front view of the same. 80

Fig. 12 is a diagrammatic view of apparatus and circuits for carrying out certain features of this invention.

Fig. 13 is a diagram showing a modification which may be made in the circuits. 85

Like reference numerals and letters are in use throughout the specification to indicate the corresponding parts.

Referring now to Figs. 1 to 4, inclusive, a vertical board 1 is provided having arranged on its two vertical sides racks 2, 2. A bar 3 has attached to its two ends, respectively, cords 4 which pass over pulleys 5 at the top of the board and have their other ends attached to weights 6. The bar 90 3 can, therefore, be easily set in various horizontal positions, engaging corresponding teeth in the two racks 2, 2. Slidable on the bar 3 is a block 7, preferably of insulating material. The spring 8, as shown in Fig. 4, which is an under plan view of the block 7, is cut away at its ends so as to leave a U-shaped portion, and the spring 9 is cut away so as to leave a portion between the two limbs of the spring 8. The springs 8 and 9 95 are connected to suitable terminals, as shown. On an extension of the rod a pulley 10 is arranged and over this pulley passes a cord one end of which is attached to the piece 7 and the other end to a weight 100 11. Mounted on the spindle carrying the pulley 10 and rotatable therewith is a spur

wheel 12. The spur wheel 12 gears with a smaller spur wheel 13 carried on a spindle rotatable in the extension of the bar 3, and this spindle carries a governor 14. Pins 15 5 are inserted in the board in horizontal rows, so that when the bar 3 is set in any given position, the springs 8 and 9 move in front of the particular row of pins and the spring 9 engages therewith. A switch is provided 10 on the block 7. This switch comprises an arm 16 pivoted at 17 and adapted to make contact with a contact 18, or to be moved out of contact therewith to a position 19, shown in broken lines. A rod or bar 20 is 15 pivoted to the arm 16 and is slidable in guides 21. The ends of the bar 20 extend beyond the block 7 and are adapted to engage the sides of the racks 2 and 2 when the block 7 is moved as hereafter referred to.

20 The switch arm 16 and the contact 18 are connected, respectively, to the two terminals which are connected to the springs 8 and 9.

At the bottom of the board a portion is 25 cut away and a fixed spindle 22 has mounted on it four cylinders 23, 24, 25 and 26, which cylinders are freely rotatable on said spindle. Each cylinder has attached to it a toothed wheel 27, into the teeth of which the end of a spring 28 can engage so as to 30 hold the cylinder in position, but allow of its being turned easily by hand. Pins are arranged on each of the cylinders as follows: On successive generating lines of the surfaces there are arranged, respectively, 35 one pin, two pins, three pins . . . ten pins. The surfaces of the cylinders are just flush with the front surface of the board, so that the rollers can be set to provide rows of pins, as arranged in the upper part of the 40 board.

The device described, as hereinbefore mentioned, is particularly adapted for use in an automatic telephone system of the two-wire type, such as described in the 45 specification of said British Letters Patent No. 1298 of 1910, and the method of using it and of setting up the calls will now be described. The springs 8 and 9 are connected in series with the ordinary calling device, 50 or in place of the ordinary calling device. The various subscribers that it is desired to call, for example, those most frequently desired to be called by the particular calling party, have allotted to each of them one 55 particular row of pins. For example, in Fig. 1 pins are shown in the first level for calling (reading from right to left) the number 5323 and in the second level the number 6614. It will be understood that 60 the pins of the particular subscriber to be called are kept permanently in the board. If this calling party desires to call the subscriber allotted to the first level, for example, and against which level the called 65 party's name appears, it is only necessary

for the calling party to move the bar 3 so that the springs 8 and 9 come opposite the top level of pins, move the block 7 from left to right against the action of the weight 11, and then release the block 7, when the latter 70 is returned by the weight 11. While the block 7 is being moved from left to right, the arm 16 is in contact with the contact 18, so that the springs 8 and 9 are short-circuited and consequently their separation as 75 they pass over the pins 17 is without effect. When the block reaches the right-hand side of the board, the right-hand end of the rod 20 engages the right-hand rack 2, and the switch arm 16 is moved to the position 80 shown in broken lines at 19. The short-circuit is therefore removed from the springs 8 and 9, and as the block returns the pins 15 cause the necessary impulses to be sent. That is to say, there are five breaks in 85 the circuit, then a pause, then three breaks, then a pause, then two breaks, then a pause and then three breaks. When the block 7 reaches the left-hand side of the board, the left-hand end of the rod 20 engages the 90 left-hand rack 2, and consequently the switch arm 16 is moved over to make contact with the contact 18, thereby leaving the block 7 ready for the next call. The return movement of the piece 7 is governed by the 95 governor 14.

It will thus be seen that after the pins are set up for the calls of particular parties to be called the calling party does not have to consider what the number of the called 100 party is, but merely has to move the bar 3 to the particular position allotted to the particular party to be called.

The cylinders 23, 24, 25 and 26 are provided so that, instead of altering the pins 105 fixed in the board, a call may be set up and left set up for any length of time desired. For this purpose the cylinders are merely rotated so that the particular groups of pins come into the horizontal level over which 110 the springs 8 and 9 move when the bar 3 is in its lowest position.

The apparatus described is for calling a number of a called party consisting of four digits, but it is obvious that the apparatus 115 may be constructed for calling numbers of any number of digits.

Referring now to Figs. 5 to 9, inclusive, another calling device operating on the principle of the calling device described in connection with Figs. 1, 2, 3 and 4 will now be described. Mounted on a suitable base 30 are standards 31 and rotatable in the standards is a shaft 32 which is of square cross-section beyond the parts fitting in the bearings. A number of disks 33 are mounted on the shaft, and for this purpose the disks have radial slots 34 and in these slots are provided springs 35. Collars 36 are provided on the shaft 32 and the disks fit be- 125 130

tween these collars. They can be slipped onto the shaft, the springs 35 holding them in position. Around the circumference of the disks 33 are arranged rings 37 held in position by screws, and between these rings and the disks are arranged radial pins or strips 38. These pins can be moved radially and are curved at their inner ends, the depressed portion being adapted to fit into 5 one of two corresponding annular depressions 39 in the disks (see Fig. 8 and the lower portion of the disk or the right-hand side of Fig. 7). The pins 38 can, therefore, be placed in one or the other of two positions—that is, so that they either project or do not project beyond the periphery of the disk.

Mounted on the standards 31 is a bar 40, and slidable on this bar is a block 41 of insulating material. On the under side of the piece 41 is screwed a spring 42 which can be depressed by a spring-pressed handle or plunger 43. The spring 42 is provided with a tooth 44 which is adapted to engage in 20 slots 45 in the under side of the bar 40. Two springs 46 normally in contact are supported on the block 41, and outside of these two springs are two springs 47 insulated therefrom but normally keeping the springs 25 46 in contact. The springs 47 extend beyond the springs 46, as shown, and two guard-pieces 48 are arranged outside them. On the pins 38 forcing the springs 47 out of contact the springs 46 also separate.

35 Mounted on a spindle 49 rigidly secured to the standard 31 is an arm 50. Rotatable on the spindle 49 is a ratchet wheel 51 rigidly secured to a spur wheel 52. A spring-pressed pawl 53 is carried by the arm 50 and 40 is adapted to engage the ratchet wheel 51. A clock spring 54 surrounds the spindle 49 and has one end attached thereto, the outer end of the spring being attached to a pin 55 on the arm 50. The spur wheel 52 gears 45 with a spur wheel 56 carried on the shaft 32. The shaft 32 also has rigidly attached to it a spur wheel 57 which gears with a spur wheel 58 mounted on a spindle rotatable in a bearing formed by an extension of 50 the standard 31. Mounted on the latter spindle is a worm wheel 59, which worm wheel meshes with a worm 60 on the spindle of a governor 61.

Attached to a suitable standard 62 is a 55 spring 63 having an angular projection 64 on its curved end 65, which latter is adapted to engage in the slot 34 of the disk 33 adjacent to the gearing described.

Mounted on the shaft 32 is a ratchet wheel 60 66 with which engages a spring-pressed pawl 67, so as to allow the shaft 32 to rotate only in one direction.

The apparatus is provided with a casing 68 having a slot 69 to allow of the movement of the arm 50, and on the top of the

casing are provided tablets 70 carrying the names of the subscribers who can be called. The block 41 is provided with a pointer 71 which can be set opposite the name of the particular subscriber to be called and indicates when the block 41 is in the correct position for so doing.

Each of the disks is allotted to a particular subscriber to be called, and the pins are so set as to effect the necessary impulses to 75 operate the switches. For example, the disk shown in Fig. 6 is set to call the subscriber whose number is 5423. The springs 46 are connected in series with an ordinary calling device.

To effect a call the plunger 43 is depressed and the block 41 slid along the bar until the springs 47 come into the path of the projecting pins of the disk allotted to the particular subscriber to be called. It will be seen that 80 the block 41 can only be moved on the bar 40 when the disks are in normal position, as otherwise the guard-pieces 48 would engage the disks and prevent movement. When the block 41 is in the proper position the plunger 43 is released, the tooth 44 engaging the corresponding slot 45 in the under side of the bar 40. The arm 50 is then depressed. During this movement the pawl 53 slips over the teeth of the ratchet wheel 51, the shaft 90 32 being prevented from rotation, as also the ratchet wheel 51, by means of the ratchet wheel 66 and the pawl 67. In the normal position of the arm 50 it engages the projecting portion 64 of the spring 63 and keeps 100 the end 65 of this spring in the slot 34 of the disk adjacent to the gearing. After a small movement of the arm 50 the end 65 of the spring 64 moves out of the slot 34. During the downward movement of the arm 50 the 105 spring 54 is wound up. On the release of the arm 50 it is returned by the spring 54 and the pawl 53 rotates the ratchet wheel 51, and thereby the shaft 32 through the medium of the spur wheels 52 and 56. The projecting pins 38 separate the springs 47 and thereby permit the springs 46 to separate, thus sending the necessary impulses to the line to effect the automatic switching. The governor 61, it will be seen, controls the 115 speed of the disks 33 as the arm 50 returns to normal position. Just before the arm 50 reaches its normal position it engages the spring 63, which is thereby depressed and enters the slot 34 in the disk adjacent to the 120 gear as soon as the latter and with it all of the other disks return to normal position, thereby preventing overrunning of the disks.

In the construction of calling device so far described the arrangement has been such 125 that a pair of springs are separated to send impulses. However, it is obvious that in any of the constructions of apparatus it can be arranged so that contacts would be closed, as would be necessary, for example, in a 130

three-wire type of "Strowger" or other similar system, additional contacts being provided for sending supplementary impulses that may be required.

- 5 In practice, the bulk of the calls of a telephone subscriber are made to a very limited number of subscribers, say twenty or thirty, and a calling device constructed according to this invention enables these subscribers to
10 be called with a single selective operation on the part of the calling party, thereby making it simpler and easier to effect a call and tending to prevent errors in making a call. A calling device constructed according
15 to this invention is, therefore, particularly applicable for use with telephone systems having a large number of subscribers, as in this case the subscribers have numbers consisting of several digits and consequently
20 necessitating normally several selective operations on the part of the calling party.

As hereinbefore mentioned, according to another feature of this invention means are provided whereby after a call is effected by
25 any type of calling device, and before the calling party has any necessity for removing his receiver from the hook, an indication is given him when the called party removes his receiver from the hook. Also, if
30 necessary or desirable, an indication is given to the calling party if the called party is busy. Furthermore, if the called party is busy all the switches that have been operated are released, this obviously being an additional advantage, as it enables the switches to deal with a larger number of calls than would otherwise be possible. Should a calling device be constructed and arranged so that the call is repeated at intervals, as hereinbefore referred to, it may be unnecessary to provide means for indicating when the called party is busy, the calling device being arranged to operate until the calling party
40 gets the indication that the called party has removed his receiver from the hook. According to the preferred method of carrying this part of the invention into effect, the two indications to be given to the calling party are effected broadly by the following
45 means: In a two-wire type of automatic telephone system, as described, for example, in the specification of said British Letters Patent No. 1298 of 1910, when the called party removes his receiver from the hook the direction of flow of current to the calling party is reversed, and this reversal of current is employed to indicate or control the indication that the called party has removed his receiver from the hook. To give the indication when the called line is busy the connectors are so constructed and arranged that the line of the calling party is opened, this opening of the line indicating or controlling an indication to the calling party
55 that the called party is busy. The opening

of the calling party's line as just referred to also serves to release all the switches operated by the calling party.

One specific method of carrying this part of the invention into effect will now be described in detail in connection with a calling device of the type shown and described in connection with Figs. 4 to 9, inclusive, of the accompanying drawings. In Figs. 10 and 11 are shown the modification or addition to the calling device which is necessary for carrying this part of the invention into effect. Attached to one standard 31 is a bracket 80 carrying an electromagnet or relay 81 and a polarized electromagnet 82. Attached to the bracket is a block of insulating material 83 carrying springs 84, 85, 86, 87, 88 and 89. Mounted on the shaft 32 is a collar 90 having radially projecting arms 91 and 92 of insulating material, said arms being set at an angle, as shown in Fig. 11. With the shaft 32 in its normal position, the arm 91 separates the springs 84 and 85, while the springs 86 and 87 are in contact and the springs 87, 88 and 89 are separated. The armature 93 of the electromagnet 81, on being attracted, forces the three springs 87, 88 and 89 into contact. When current flows in one direction through the polarized electromagnet, the armature 94 holds the armature 93 of the electromagnet 81 in its attracted position. Fig. 12 shows diagrammatically a calling substation F provided with a calling device of the type shown and described in connection with Figs. 5 to 9, inclusive, of the accompanying drawings, and having the additional apparatus described in connection with Figs. 10 and 11, and the trunk line leading to a called substation F', the call being shown as completed. So far as the ordinary substation apparatus and the automatic apparatus employed in effecting a connection is concerned, the circuits correspond to those shown in the specification of said British Patent No. 1298 of 1910, all circuits and apparatus being omitted which are not directly concerned in the present invention. At H, K, L and H' is a line switch, selector, connector and line switch, respectively, as in the specification referred to. The connector L is similar to the connector L of the specification referred to with the following exception: The relay 272 corresponds with the relay 272 of the specification referred to except that two additional contact springs are provided which are brought into contact on the relay being energized. One of these contact springs 95 is connected to ground and the other spring 96 is connected to one terminal of a special relay 97, the other terminal of which is connected to battery B. The relay 97 is provided with three contact springs and the upper trunk is broken, one side being connected to the two springs 98
125
130

and 99 and the other side to the spring 100. Upon the relay 97 being energized the spring 100 is moved out of contact with the spring 99 and into contact with the spring 98. The three springs just referred to are widely separated, so that the line is opened for an appreciable time, or, to obtain a long break, any suitable dash-pot may be connected with the armature of the relay.

10 The substation F is provided with the ordinary apparatus, as in the specification referred to, namely, a telephone hook and contacts therefor, a receiver and transmitter, a ringer and a condenser. At the telephone hook an auxiliary contact 101 is provided, this contact 101 and the upper contact being so constructed that the switch hook, on rising, does not break contact with the contact 101 before it makes contact with the upper contact.

15 The subscriber desiring to make a call sets the block carrying the impulse springs 46 opposite the name of the subscriber to be called, as described in connection with Figs. 5 to 9, inclusive. He then depresses the arm 50 and on its return movement the disks 33 begin to move with the shaft 32. Before any impulses are sent the arm 91 allows the two springs 84 and 85 to come into contact. This 20 closes a circuit over the line from the lead 157, contact 101, impulse springs 46, springs 84 and 85, springs 87 and 86 to the line 158. The line switch H is consequently operated in the ordinary manner and as described in 25 the specification referred to. The impulses are then sent to operate the selector K and the connector L. Directly after the sets of impulses have been completed the arm 92 separates the springs 86 and 87 and immediately 30 closes the springs 87, 88 and 89. A circuit is thereby closed through the electromagnets 81 and 82, this circuit being from the line 157, contact 101, impulse springs 46, spring 89, spring 88, magnet 81, magnet 82 35 and the line 158. The magnet 81 attracts its armature and holds the springs 87, 88 and 89 in contact and the spring 87 out of contact with the spring 86 after the arm 92 has moved onward.

40 If the called subscriber answers he reverses the direction of the current in the calling subscriber's line in the usual manner by means of the usual back bridge relay (not shown) which operates the springs 273 to reverse the connection of the relay 274 to the talking conductors. This reverses the current in the polarized electromagnet 82 and, upon its armature moving, it strikes a bell 275, or gives any other signal to indicate to the calling subscriber that the called subscriber has answered. The calling subscriber can then remove his receiver from the hook and the line is not broken, as the receiver hook does not break contact with 45 the contact 101 until it makes contact with

the upper contact. Upon the hook completing its upward movement the circuits of the magnets 81 and 82 are broken, so that upon the hanging up of the receiver the switches are released, the springs 84 and 85 having 50 been separated and all of the auxiliary device being in normal position.

55 If the called subscriber is busy all of the switches are released in a manner to be described. The relay 272 is energized if the 75 called line is busy. This closes the springs 95 and 96, thereby energizing the relay 97, so that contact between the springs 99 and 100 is first broken and then after some interval of time contact is made between the 80 springs 98 and 100. This opening of the circuit breaks the circuit of the magnet 81, thereby allowing its armature to fall back and release all the switches that have been operated. The relay 97 has its springs separated to a somewhat considerable distance, so that the line is opened for a comparatively long interval of time, as hereinbefore referred to.

60 Instead of arranging the springs at some 90 distance apart, as just mentioned, or of providing a dash-pot for the armature of the relay 97, the arrangement shown in Fig. 13 may be employed. In place of the relay 97 there is arranged a relay 102 which is quick 95 to energize but slow to deenergize. The line is broken and connected to the two contact springs 103 and 104 of this relay, while the circuit of the relay 102 is completed through the springs 105 and 106. When, therefore, 100 the springs 95 and 96 are closed by the energization of the relay 272, the relay 102 is energized, but its armature breaks its own circuit so that it deenergizes slowly and the connection between two parts of the line is 105 not completed for some little time. To aid in this the armature of the relay 102 may be loaded, so that it does not move until the energizing current has nearly reached its maximum value. The deenergization of the 110 relay 81 may serve to operate a bell 276 or give any other suitable signal to indicate that the called line is busy. It may be noted that the bells 275 and 276 may be of different size or may be arranged in any manner 115 to give different signals.

65 The circuit at the connector is temporarily opened, as just described, and not permanently opened, as might be more easily arranged, for the reason that if the circuit 120 were permanently opened, upon a call being made in the ordinary way to a busy subscriber, the calling subscriber would not get the ordinary busy signal.

70 It is obvious that various modifications 125 can be made in carrying the various features into effect, those given above being merely by way of example.

75 What I claim as my invention is:—

1. In a telephone system, means for con- 130

- necting a calling and a called telephone line, means under the control of the calling telephone to signal the called telephone, means for indicating to the calling party before he 5 removes his receiver from the hook that the called party has answered.
2. In a telephone system, a plurality of subscribers' lines, means including automatic switches for establishing connection 10 between two of said lines, and means for indicating to a calling party before he has removed his receiver from the hook that the called party has answered.
3. In a telephone system, a plurality of 15 subscribers' lines, means including automatic switches for establishing connection between two of said lines, a calling device on the calling line, means for operating said device to control the operation of said 20 switches without removal of the receiver from the hook at the calling station, and means for indicating to the calling party before he has removed his receiver from the hook that the called party has answered.
- 25 4. In a telephone system, a plurality of subscribers' lines, means including automatic switches for establishing connection between two of said lines, a calling device on the calling line, means for operating said 30 device to control the operation of said switches without removal of the receiver from the hook at the calling station, a signal at the calling station, means controlled by the response of the called subscriber for re- 35 versing the current on the calling line, and means controlled by said reversal of current for operating said signal before the calling subscriber has removed his receiver from the hook.
- 40 5. In a telephone system, a plurality of subscribers' lines, means for establishing a connection between two of said lines, a signal on the calling line, and means for positively operating said signal when an at- 45 tempt is made to establish connection with a busy line to thereby indicate to the calling subscriber that the called line is busy, a source of current for supplying current to the line for talking, means for removing 50 said source, said signal responsive to the removal of said current.
- 55 6. In a telephone system, a plurality of subscribers' lines, means including automatic switches for establishing a connection 55 between two of said lines, a signal on the calling line, and means for positively operating said signal when said automatic
- switches attempt to establish connection with a line which is busy, a source of current for supplying current to the line for talking, means for removing said source, 60 said signal responsive to the removal of said current.
7. In a telephone system, a plurality of subscribers' lines, means for establishing a connection between two of said lines, a signal on the calling line, means for positively operating said signal when an attempt is made to establish connection with a busy line to thereby indicate to the calling subscriber that the called line is busy, and means for automatically releasing said connection when said signal is operated, a source of current for supplying current to the line for talking, means for removing said source, 70 said signal responsive to the removal of said current.
8. In a telephone system, a plurality of subscribers' lines, means including automatic switches for establishing a connection 75 between two of said lines, a signal on the calling line, means for positively operating said signal when said automatic switches attempt to establish connection with a line which is busy, and means for automatically releasing said automatic switches when said signal is operated, a source of current for supplying current to the line for talking, means for removing said source, said signal responsive to the removal of said current.
9. In a telephone system, a line, a telephone 80 for said line, automatic progressively movable trunking means for said line for extending a connection toward a called line, an impulse sender at the telephone for controlling said means, a battery for operating pur- 85 poses, a signal at the telephone responsive to current of one kind over said line to operate the signal in one manner to indicate that the called line is busy and responsive to current of another kind to operate the signal in a different manner to indicate that the called party has answered, another signal at the telephone, said signal responsive to current of a different character to indicate that the called line is busy. 90
